UNITED STATES PATENT OFFICE.

HERMINE BELLING-KÜNG, OF ZURICH, SWITZERLAND.

DRESS-FORM.

1,246,224.

Specification of Letters Patent.

Patented Nov. 13, 1917.

Application filed June 8, 1915. Serial No. 32,865.

To all whom it may concern:

Be it known that I, HERMINE BELLING-KÜNG, a citizen of Germany, and a resident of Zurich, Switzerland, have invented certain new and useful Improvements in Dress-Forms, of which the following is a specification.

This invention relates to a dress form which may be adjusted both vertically and laterally in a novel and simple manner.

In the accompanying drawing:

Figure 1, is a longitudinal section partly in side view of a dress form embodying my invention;

Fig. 2, a cross section on line d^1, d^2 , Fig. 1; Fig. 3, a cross section on line e^1, e^2 , Fig. 1; Fig. 4, a side elevation, and Fig. 5, a cross section on line a^3, a^4 , Fig. 1.

The device comprises essentially, a pair of upright telescoping rods d, e , mounted on a suitable base (not shown) and which may be adjustably connected by means of a set screw f . The body of the dress form is composed of a lower rump section c , an intermediate bust section b , and an upper neck section a . The rump section c is provided with an upper projection 10 adapted to be received within a corresponding socket of the bust section b . Otherwise the construction of the rump section is identical with that of the bust section so that the description of the latter will apply to the former.

The bust section is formed of four quadrantal members b^2, b^3, b^4, b^5 , which are adjustably connected to each other by pins

q, r, s, t each pin being fast in one of the members and loose in the other member. The pins are engaged by the surface grooves of sheave wheels m, n, o, p having spanner holes, so that the wheels may be turned by means of a suitable key Z . The threaded eyes of the sheaves engage screw bolts h, i, k, l , secured at their inner ends to a collar g carried by rod d . It will be seen that by turning the sheave wheels, pins q, r, s, t , will be forced either outward or inward to correspondingly spread or contract members b^2, b^3, b^4, b^5 , and accordingly either increase or decrease the width of the bust section.

Into the neck piece a are counter sunk four nuts, u, v, w, x engaged by screws s^1, s^2, s^3, s^4 . A bipartite resilient strap r^1, r^2 encompasses neck piece a and has apertures for the accommodation of screws s^1, s^3 , and slots for the accommodation of screws s^2, s^4 . By turning the screws, the strap may be either expanded or contracted to correspondingly increase or decrease the diameter of the neck piece.

I claim:

A dress form comprising a rod, a plurality of quadrantal members encompassing the same, pins connecting said members, sheaves engaging the pins, said sheaves having threaded eyes, screw bolts engaging said eyes, and a collar on the rod, which collar carries the screw bolts.

HERMINE BELLING-KÜNG.
